JAMES B. STEVENSON, OF BLOOMINGTON, ILLINOIS.

Letters Patent No. 83,887, dated November 10, 1868.

IMPROVEMENT IN RETURN-DRIPS FOR PUMPS.

The Schedule referred to in these Letters Patent and making part of the same.

To all whom it may concern:

Be it known that I, JAMES B. STEVENSON, of Bloomington, in the county of McLean, in the State of Illinois, have invented a new and improved Mode of Conveying the Waste Water from Pumps Used in Wells and Cisterns, Back to the Same; and I do hereby declare that the following is a full and exact description thereof, reference being had to the accompanying drawings, and to the letters of reference marked thereon.

The nature of my invention consists in the combination of its several parts, attached to any pump-stock used in wells and cisterns, which can be used for conveying the warm water in the pump-stock, when drawn up, back into the well, thereby saving all loss of water from the spout, and by use of which the platform over the wells, about the pumps, can be kept free from the drippings from the spouts.

A represents a funnel, attached to the conductor B. This conductor is connected by the hinge E to the pipe F, which passes through the platform beside the pump-

stock H. The guide C, which serves to direct and limit the motion of the conductor B, and the spring D, which presses the conductor outward, are attached to the pump-stock, as represented in the drawings.

Its operation is simple. When water is wanted from the well, the conductor is easily pressed back by the weight of the bucket, or other vessel used, which, by the action of the spring, immediately resumes its place, conveying all waste water into the well.

It may be manufactured of wood, metal, or other suitable material.

What I claim as my invention, and for which I desire a patent, is—

The combination of the tunnel, conductor, pipe, hinge, guide, and spring, all arranged as described, and for the use specified.

JAMES B. STEVENSON.
